COVER RETAINER FOR CANS

John A. Hopwood, Great Neck, N. Y.

Application February 4, 1941, Serial No. 377,287

10 Claims. (Cl. 220—55)

This invention provides a means for retaining a cover in place upon a can and while adapted for general uses is primarily intended for use on cans, such as are used for the delivery of milk and cream. All parts of such cans must be so constructed and arranged that they will be capable of thorough sterilization at the creamery and they must be also susceptible of being tightly sealed in such a way as to preclude contamination of the milk during shipment. The present invention provides such an arrangement and at the same time may be so constructed as to provide for dispensing of milk or cream from the can in desired quantities.

Cans of the type employed for the purposes stated comprise a body, the upper end of which is formed into a so-called "breast" on which is superimposed a neck outwardly flared to produce a lip or bowl. The can cover is commonly provided with a tubular skirt or rim adapted to fit into the neck to close the can. It is the practice generally to secure the cover in place by wired seals which extend through perforations in the cover and through handles on the body of the can.

In accordance with the present invention, the can is conventional while the skirt of the cover is preferably provided with a rubber gasket adapted to seat in the flared lip portion of the neck. The can cover is, however, provided, interiorly of the can, with a series of pivoted retaining fingers which are operable from the exterior of the cover to grip the interior of the can at its breast and draw the cover down tightly upon the gasket to form a tight seal and secure the cover against inadvertent displacement. These retaining fingers, however, may be manipulated from the exterior of the can to release the cover and permit of its removal.

The cover may also be provided with an appropriate filling and sterilizing opening adapted to be normally closed by a removable closure and in said cover are additionally provided air inlet and liquid outlet means adapted to coact in dispensing the contents of the can as hereinafter described. Locking means cooperates with the closure and with gaskets forming part of the air inlet and liquid outlet means to hold all of these parts in position, so that they cannot be surreptitiously removed without indicating such fact.

Features of the invention, other than those adverted to, will be apparent from the herein-after detailed description and claims when in conjunction with the accompanying drawings.

The accompanying drawings illustrate one 55

practical embodiment of the invention, but the construction therein shown is to be understood as illustrative, only, and not as defining the limits of the invention.

5 Figure 1 is a plan view of a can cover embodying the present invention with a closure cap, forming part of the invention, removed.

Figure 2 is a section on the line 2—2 of Figure 1 with the closure cap in place.

10 Figure 3 is an underneath plan view of the cover removed from the can with one of the retaining fingers removed, but indicated in dotted lines.

Figure 4 is a section on the line 4—4 of Fig. 1.

15 Figs. 5 and 6 are cross-sections of modified forms of construction.

Fig. 7 is a section on the line 7—7 of Fig. 6.

20 Referring to the drawings, 1 indicates the body of the can having a breast 2 and a tubular cylindrical neck 3, the upper end of which is flared to provide the lip 4. The cover comprises a cover plate 5 having a depending tubular cylindrical skirt or rim 6, adapted to fit into the neck 3. The lower end of the skirt may be slightly contracted 25 as shown.

25 About the cover plate is an upstanding tubular cylindrical wall 7 which extends for an appreciable distance above the plate and is open at its top. Juxtaposed with the cover plate but exterior of the wall 7 is an annular "umbrella" 8. All of these parts are firmly secured together by riveting, welding, soldering or the like, so that they constitute, in effect, an integral structure.

30 Mounted centrally of the cover plate 5 is a tubular hub 9. A portion of this hub projects above the cover plate and is threaded at 10, while the greater portion of the hub projects below the cover plate and is provided at its lower end with a series of pairs of brackets 11. Across each pair

35 of brackets is a pivot pin 12 and on each pivot pin 12 is a retaining finger 13. These retaining fingers are each provided with a bayonet slot 14, so that they can be individually assembled on or removed from the pins 12 and each of said fingers is, in effect, a bent lever of the first class, having a power arm 15 and a work arm 16.

40 The several levers or retaining fingers extend in radial directions with their several power arms grouped together in closely spaced relation about the axis of the hub within a chamber 17 in the lower end of the latter. To permit close spacing these ends of the levers are tapered as shown at 18. Figures 2 and 3 show very clearly the 45 relation of these levers in the chamber 17.

Positioned within the chamber 17 above the

levers is a pressure disk 19 and bearing on this pressure disk is a stud 20. This stud extends upwardly through the tubular hub to a point above the top of the threaded portion 10 and is there firmly attached to a hollow operating member or head 21, the interior of which is threaded to screw on to the threaded portion 10. The retaining fingers 13 are so shaped and proportioned that when the head 21 is unscrewed with respect to the threaded portion 10, the retaining fingers will gravitate into the dotted line positions shown in Figure 2 to permit the cover to be placed on or removed from the can.

However, when the cover is placed on the can and the head 21 screwed down, it exerts pressure upon the pressure disk 19 which swings the retaining fingers upwardly into the full line position in which they engage with the breast of the can and by continued pressure exerted by the head 21, the cover may be forced firmly into position into the neck.

As shown best in Figure 2, the depending skirt 6 of the cover is provided with an annular stop 22 and below which stop is positioned an elastic gasket 23 which, when the cover is forced into the neck, seats within the flared lip portion 4 to produce a liquid tight joint therewith.

To facilitate operation of the head 21, it is preferably provided with radial wings or arms 24. The cover retaining position of the head 21 and arms is indicated in full lines in Figure 2 while the dotted line positions of these parts indicate those which will permit of the removal or replacement of the cover.

If desired one of the wings or arms 24 may be perforated and a perforated bracket similar to the bracket 25 may be mounted on the wall 7 or on the cover plate 5 and an ordinary wired seal may be passed through the perforations of both parts, so that after the can has been filled and the cover secured in place by screwing down the head 21, the wired seal will guard the can against surreptitious tampering. However, in the preferred form of the invention other and additional adjuncts hereinafter described are preferably associated with the structure which serve the same and additional purposes.

It is to be understood that the invention may be used as thus far described so as to utilize merely the retaining means of the can cover for there is a pronounced commercial need for a satisfactory cover retainer in connection with the delivery of milk. The structure which I have described is such a retainer. All of the parts may be readily dismantled for cleaning and sterilization. By unscrewing the head 21, the head and its stud 20 may be removed and then the retainers 13 can be individually unhooked from their pivots 12 to release the pressure disk 19, and when all these parts are separated, they may be thoroughly cleaned and, if desired, they can be re-assembled and sterilized after assembly, as will hereinafter be more fully explained.

In the preferred form of the present invention, I so constitute the can cover that it will provide for the dispensing of its contents without removal of the cover and in the invention as shown in the drawings, there is thus provided means whereby air may be introduced into the can through the cover to force the liquid out of the can through a dispensing tube which is also introduced into the can through the cover.

In this showing the cover plate 5 is provided with two apertured bosses 26 and 27, as shown

best in Figure 4. Through the boss 26 extends an air inlet tube 28a flanged at its top to seat on the boss and in the upper end of this tube is fitted a rubber nipple valve 28 provided at its top with a flange 29 which constitutes a gasket. The nipple valve 28 is provided with a closed end having therein one or more slits 30 which are adapted to be opened by pressure admitted into the chamber of such valve. The upper face of the boss 26 has two radial notches 31 therein so that if the pressure in the can becomes too great the nipple valve may be collapsed sufficiently to permit the pressure to bypass the nipple and vent to the atmosphere through the notches 31.

Into the aperture of the boss 27 is fitted a rubber sleeve 32 open at both ends but provided at its upper end with an external flange 33 which seats on the top of the boss and constitutes a gasket. Telescoping liquid delivery tubes 32a and 32b coact with this sleeve as indicated in dotted lines in Figure 2.

Positioned midway between the bosses 26 and 27 and rigidly mounted on the cover plate 5 is an upstanding post 34 having therein a circular aperture 34a. A pressure plate 35 is apertured to fit down over this post and extend laterally in opposite directions to overlie the gaskets 29 and 33. This pressure plate is cut away over the openings in the gaskets and is adapted to be forced down to a firm seat upon the gaskets to hold them and their associated rubber parts in place by means of a locking bar 36. One end of the locking bar is twisted as shown at 37 and has a tongue 38 adapted to be passed through the circular hole 34a in the post 34. This bar is made from flat stock, so that, when the flat tongue is placed in a horizontal position as shown in dotted lines in Figure 2, it may be passed loosely through the opening 34a in the post and then shifted into the full line position of this figure by rotation of the bar through 90 degrees. This tongue will then exert a camming action with respect to the opening 34a and the pressure plate 35, so that the latter is forced down tightly upon the gaskets 29 and 33 and will thus serve to hold them tightly in position.

The locking bar is bent so as to reach across the top of the cover plate to the opposite side thereof at which point it is offset downwardly, as shown at 39, in order to bear upon a removable and disruptable closure 40 seated in a filler boss 41 which surrounds the filler opening of the cover plate, as shown best in Figure 2.

Beyond the offset portion 39 the locking bar has a laterally extending angular portion 42 adapted to cooperate with the locking bracket 25 and both of these parts are perforated to receive a wired seal 43 as shown best in Figure 1. Consequently, when the locking bar is in place, it serves to anchor both the gaskets and their associated rubber parts in place, as well as the removable closure 40 of the filler opening. It also has the further function of serving to preclude release of the cover from the can as the arms or wings 24 of the head 21 project sufficiently to engage with the locking bar and consequently the head 21 cannot be unscrewed to release the cover so long as the locking bar is in its locking position and this locking bar cannot be removed from this position without breaking the wired seal 43.

After a can is cleaned, sterilized and filled and thereafter sealed by the locking bar and the wired seal 43, the retail dealer who receives the can in this condition will know that it has not

been tampered with and that the contents are guaranteed by the shipper.

When the can is in shipment, a supplementary cover 44 is adapted to be placed over the upstanding wall 7 and serves as a housing to cover and conceal all of the parts which are superimposed on the cover plate 5 and to provide a flat surface on which another can may be rested upon the first in stacked relation. The supplementary cover 44 may be held in place by a frictional fit or may be threaded or otherwise arranged to be positively secured in position.

In utilizing the foregoing invention in the retail dispensing of milk, cream or the like, the can is received at the creamery in the condition shown in full lines in Figures 1 and 2 of the drawings. The following operations are then carried out: The supplementary cover is first removed, the wired seal 43 is disrupted and the locking bar is moved into the dotted line position of Figure 2. This relieves pressure on the pressure plate 35, so that the tongue 38 may be withdrawn. The pressure plate 35 may now be removed.

The head 21 is now unscrewed so that the stud 20 is elevated so that the retaining fingers 13 may drop into the dotted line position of Figure 2 to release the cover. The cover is then removed, the fingers 13 separated therefrom and the disk 19 is taken from the chamber 17. The two rubber members 28 and 32 and tubes 28a, 32a, and 32b are removed from the bosses 27 and 26. The gasket 23 is slipped off of the depending skirt 6 and all the parts are at that time fully dismantled, so that they may be individually thoroughly cleaned including the can and the cover.

After thorough cleansing, the disk 19, fingers 13, head 21 and its stud 20 are replaced. New rubber members 28 and 32 are associated with the tubes and these are positioned in the bosses 26 and 27, respectively, the pressure plate 35 is returned into position, and the end 38 of the locking bar is passed through the opening 34a in the post 34. The gasket 23 is replaced on the cover and the cover is placed on the can. The head 21 is then screwed down tightly and the cover is locked in place.

With the parts in this condition and with the can empty, the assembly is passed to a sterilizer and the entire assembly is sterilized both exteriorly and interiorly for the closure 40 has not yet been applied. After thorough sterilization milk is introduced into the can through the filling opening in the boss 41 and thereupon the closure 40 is applied. The locking bar is then moved into the full line positions of Figures 1 and 2 and locked in place by a wired seal 43. The supplementary cover 44 is next applied and the filled can in thoroughly sterilized condition is ready for shipment.

The lodging of water due to condensed steam or otherwise in the space above the cover plate and within the upstanding wall 7 is precluded by drain holes 45 shown in Figure 2.

When the filled can is received by the retailer, he removes the supplementary cover 44, couples the dispensing tube and air inlet nipple valve 28 to appropriate dispensing mechanism and proceeds to dispense the contents as and when desired, the can remaining closed with the wired seal 43 intact. In this way the milk or cream will not be polluted, but is maintained in a safe and sterile condition.

In Figure 5 I have shown a modified form of construction. Here the hub 9 is supported on the base of a centrally located depression 45 in

the can cover. The upstanding threaded portion 10 extends into the chamber of the depression and is adapted to receive the threaded operating number or head 46 which is housed therein. The stem or stud 47 is made separate from the head but is attached to or integral with the pressure disk 43 which bears against the power arms of the retaining fingers 13 and an elastic packing 49 is housed within the head to insure

10 a tight seal.

The head 46 has a polygonal socket 50 adapted for the reception of wrench 51 but the walls of the socket are perforated at 52 so that a wired seal 53 may be affixed therethrough and through

15 a perforated ear 54 on the interior of the recess to serve as a sealed locking member and preclude surreptitious introduction of the wrench or rotation of the head. This seal must be removed before the cover can be released and removed.

20 A removable protective cap or closure 55 normally closes the recess.

In Figure 6 the cover also has a central recess 56 normally closed by a removable closure 55. A fulcrum member 57 is attached to or in-

25 tegral with the wall of this recess and has openings 58 into which may be hooked the upper ends of retaining fingers. The operating member or head is in the form of a castellated nut 60 screwed upon a stem or stud 61 which extends

30 downwardly through the cover and carries a spreader plate 62 at its lower end. This plate is notched at 63 to receive the several fingers 59 and uniformly space them circumferentially of the plate.

35 When the head 60 is screwed upon the stem, it elevates the plate 62 and spreads the fingers 59 into engagement with the can. When the head is unscrewed, it lowers said plate and the fingers descend to release the cover for removal.

40 The parts may be secured in locked position by passing a sealed locking member 64 through a perforation in the stem 61 and through the castellations of the head 60.

The constructions of Figures 5 and 6 have the advantage that the means for securing the cover on the can do not increase the can beyond standard height and the cover, moreover, has a flush top, which is of advantage in stacking.

The foregoing detailed description sets forth 50 the invention in its preferred practical form. It will be understood, however, that inasmuch as certain parts of this invention may be employed commercially without necessarily employing all, the invention is to be understood as fully commensurate with the appended claims.

55 Having thus fully described the invention, what I claim as new and desire to secure by Letters Patent is:

1. In an assembly of the character described, 60 a delivery can provided with a neck, a cover fitting the neck to close the same and provided with a filler opening, pivoted retaining fingers on the under side of the cover, an operating handle on the exterior of the cover, connections between said handle and the retaining fingers for moving the fingers into and out of engagement with the wall of the can when said handle is rotated, a closure seated in said filler opening, and a locking bar bearing against the closure of the filler opening and positioned in the path of said handle to hold said closure in position and preclude rotation of said handle to release the fingers from engagement with the wall of the can.

70 2. In an assembly of the character described,

a delivery can provided with a neck, a cover fitting the neck to close the same and provided with a filler opening, pivoted retaining fingers on the under side of the cover, an operating member on the exterior of the cover, connections between said member and the retaining fingers for moving the fingers into and out of engagement with the wall of the can when said member is rotated, a closure seated in said filler opening, a locking bar bearing against the closure of the filler opening and positioned in the path of said member to hold said closure in position and preclude rotation of said member to release the fingers from engagement with the wall of the can, and a wired seal connecting said locking bar with the can cover to preclude surreptitious release of the locking bar.

3. In an assembly of the character described, a delivery can provided with a neck, a cover fitting the neck to close the same and provided with a filler opening, pivoted retaining fingers on the under side of the cover, an operating member on the exterior of the cover, connections between said member and the retaining fingers for moving the fingers into and out of engagement with the wall of the can when said member is rotated, a closure seated in said filler opening, a locking bar bearing against the closure of the filler opening and positioned in the path of said member to hold said closure in position and preclude rotation of said member to release the fingers from engagement with the wall of the can, a wired seal connecting said locking bar with the can cover to preclude surreptitious release of the locking bar, and a supplementary cover normally covering and concealing said member and locking bar.

4. In an assembly of the character described, a delivery can provided with a neck, a cover fitting the neck to close the same, said cover having therein a filler opening, an air inlet opening and a liquid discharge opening, gaskets associated with each of the two latter openings, and a detachable closure associated with the filler opening, a pressure plate extending over said gaskets, pivoted retaining fingers on the under side of the cover, an operating member on the exterior of the cover, operative connections between said member and the retaining fingers for moving said retaining fingers into and out of engagement with the wall of the can when said member is rotated, and a locking bar for locking the pressure plate against the gaskets and the closure within the filler opening, said locking bar extending into the path of rotation of said member to preclude sufficient rotation thereof to release the retaining fingers from contact with the can wall.

5. In an assembly of the character described, a delivery can provided with a neck, a cover fitting the neck to close the same, said cover having therein a filler opening, an air inlet opening and a liquid discharge opening, gaskets associated with each of the two latter openings, and a detachable closure associated with the filler opening, a pressure plate extending over said gaskets, pivoted retaining fingers on the under side of the cover, an operating member on the exterior of the cover, operative connections between said member and the retaining fingers for moving said retaining fingers into and out of engagement with the wall of the can when said member is rotated, a locking bar for locking the pressure plate against the gaskets and the closure within the filler opening, said locking bar

extending into the path of rotation of said member to preclude sufficient rotation thereof to release the retaining fingers from contact with the can wall, and a disruptable seal connecting the locking member and the can cover to preclude surreptitious release of the locking member.

6. In an assembly of the character described, a delivery can provided with a neck, a cover fitting the neck to seal the same, said cover having therein a filler opening, an air inlet opening and a liquid discharge opening, gaskets associated with each of the two latter openings, and a detachable closure associated with the filler opening, a pressure plate extending over said gaskets, and a locking bar for locking the pressure plate against the gaskets and the closure within the filler opening.

7. In an assembly of the character described, a delivery can provided with a neck, a cover fitting the neck to seal the same, said cover having therein a filler opening, an air inlet opening and a liquid discharge opening, gaskets associated with each of the two latter openings, a detachable closure associated with the filler opening, a pressure plate extending over said gaskets, and a locking bar for locking the pressure plate against the gaskets and the closure within the filler opening, and a disruptable seal connecting the locking member and the can cover to preclude surreptitious release of the locking member.

8. In an assembly of the character described, a delivery can for milk and cream comprising a can body having a breast and a superimposed neck, a cover having a depending skirt projecting into said neck, a fulcrum member centrally positioned on the under side of the cover and having circumferentially spaced apart fulcrum openings, a plurality of retaining fingers, the lower ends of which extend downwardly into juxtaposition with the breast of the can and the upper ends of which are hook shaped and are detachably hooked through the corresponding fulcrum openings of the fulcrum member from the interior of the latter, a spreader positioned below and coaxially of the fulcrum member and centrally of the several retaining fingers, and means operable from the exterior of the cover to draw the spreader in the direction of the fulcrum member and thereby spread the lower ends of the retaining fingers into engagement with the breast of the can.

9. In an assembly of the character described, a delivery can for milk and cream comprising a can body having a breast and a superimposed neck, a cover having a depending skirt projecting into said neck, a fulcrum member centrally positioned on the under side of the cover and having circumferentially spaced apart fulcrum openings, a plurality of retaining fingers, the lower ends of which extend downwardly into juxtaposition with the breast of the can and the upper ends of which are hook shaped and are detachably hooked through the corresponding fulcrum openings of the fulcrum member from the interior of the latter, a spreader positioned below and coaxially of the fulcrum member and centrally of the several retaining fingers and circumferentially notched to individually receive said fingers and peripherally space them apart, and means operable from the exterior of the cover to draw the spreader in the direction of the fulcrum member and thereby spread the lower ends of the retaining fingers into engagement with the breast of the can.

10. In an assembly of the character described,

a delivery can for milk and cream comprising a can body having a breast and a superimposed neck, a cover having a depending skirt projecting into said neck, a fulcrum member centrally positioned on the under side of the cover and having circumferentially spaced apart fulcrum openings, a plurality of retaining fingers, the lower ends of which extend downwardly into juxtaposition with the breast of the can and the upper ends of which are hook shaped and are detachably hooked through the corresponding fulcrum openings of the fulcrum member from the interior of the latter, a spreader positioned

below and coaxially of the fulcrum member and centrally of the several retaining fingers and circumferentially notched to individually receive said fingers and peripherally space them apart, a threaded stem projecting coaxially upwardly from the spreader through the cover, and a threaded operating head exteriorly of the cover and rotatable on said stem to draw the spreader in the direction of the fulcrum member and thereby 10 spread the lower ends of the retaining fingers into engagement with the breast of the can.

JOHN A. HOPWOOD.
